(57) CLAIM

The ornamental design for an eyewear merchandising unit, as shown and described.

DESCRIPTION

FIG. 1 is a top plan view of a first embodiment of our design, the bottom plan view being the same;

FIG. 2 is a front elevational view of a first embodiment thereof, with side and rear elevational views being the same;

FIG. 3 is a top plan view of a second embodiment thereof, with the bottom plan view being the same;

FIG. 4 is a front elevational view of a second embodiment thereof, with side and rear elevational views being the same;

FIG. 5 is top plan view of a third embodiment thereof, with the bottom plan view being the same;

FIG. 6 is a front elevational view of a third embodiment thereof, with side and rear elevational views being substantially the same;

FIG. 7 of a top plan view of a fourth embodiment thereof, with the bottom plan view being the same; and,

FIG. 8 is a front elevational view of a forth embodiment thereof, with the side and rear elevational views being the same.
